UNITED STATES PATENT OFFICE.

EDWARD B. HESS, OF BROOKLYN, NEW YORK.

WIND-SHIELD FOR AUTOMOBILES.

1,244,854.

Specification of Letters Patent. Patented Oct. 30, 1917.

Application filed May 26, 1916. Serial No. 100,082.

To all whom it may concern:

Be it known that I, EDWARD B. HESS, a citizen of the United States, residing in Brooklyn, in the county of Kings and State 5 of New York, have invented certain new and useful Improvements in Wind-Shields for Automobiles, of which the following is a specification.

This invention relates to wind shields especially adapted for use in automobiles. 10 Such wind shields are commonly made in sections so mounted that they may be raised or lowered into or out of the direct line of vision or set at an angle relatively thereto, 15 to suit varying conditions.

According to my present invention, I provide a wind shield which is made in three parts or sections, the main lower one of 20 which may be fixed to stand in a vertical position or may be hinged to swing inward. The upper section is pivotally mounted to swing outward to a position above the direct line of vision, while a third or auxiliary section is made to stand vertically parallel 25 with the main lower section or close to it, to swing upward into the direct line of vision below the upper section or inward with the lower section. Said auxiliary section is also capable of swinging inward 30 while raised if desired. The organization is such that when desired the front of the automobile may be completely closed by the upper and lower shield sections, or the upper section may be held in a vertical plane in 35 the direct line of vision while the lower sections are swung inward, or the upper section may be extended to assume a position above the direct line of vision while the lower sections are either in open or closed positions. 40 The organization is also such that the auxiliary lower section may be raised to the direct line of vision when the upper section is extended to serve as a rain guard while the main lower section is in open or closed position, 45 and furthermore, the auxiliary lower section is so mounted that when elevated it may be held in a vertical plane or it may be moved inward to a position above the lower section and in rear of the vertical 50 plane thereof.

In the embodiment of my invention shown in the accompanying drawings the upper section of the shield is hinged directly to two rigid standards rigidly mounted on opposite sides of the front portion of the automobile and the two lower sections are also

pivotedly connected to said rigid standards, such pivotal connection being preferably, as shown, midway between the upper and lower ends of the standards, the standards 60 being provided with rigid laterally projecting brackets or supports in which the auxiliary section is pivoted. The upper shield section consists of a transparent pane or plate having a frame which extends across 65 its top on opposite sides, leaving its lower edge frameless. Each of the lower sections consists of a transparent pane or plate arranged in a frame which extends across its lower edge and on opposite sides, leaving its 70 upper edge frameless. By this construction when the shield sections are in closed position an unbroken field of vision is afforded not in any way interfered with by parts of the shield frame and it will be observed also 75 that when the upper shield section is extended and the auxiliary section is raised to a vertical position above the main lower shield section it slightly overlaps the upper portion of the lower shield section and thus 80 the entrance of rain and dust is prevented.

In the accompanying drawings:

Figure 1 is a front elevation, showing the upper shield section adjusted properly to act as a rain guard, the main lower section 85 in normal or closed position and the auxiliary section swung outward and upward to a substantially vertical position beneath the upper section of the shield.

Fig. 2 is a similar view but with the auxiliary section lowered.

Fig. 3 is a sectional view with the parts in the position shown in Fig. 1 and showing by dotted lines how the auxiliary section when raised may be swung inwardly in order 95 that its front face may be readily cleaned.

Fig. 4 is a sectional view, showing the upper section lowered and the two lower sections swung inward for ventilating purposes.

Fig. 5 is a sectional view showing the three sections in closed or vertical position.

Figs. 6 to 8, inclusive, are diagrams, showing different positions of the three shield sections.

Fig. 9 is a detail view of the locking devices applied to the lower shield sections and by means of which they may be held in their adjusted positions.

A part of the hood or casing of an automobile is indicated at A and the wind shield is located in rear thereof. Standards B rise

100

105

110

from the automobile body or casing on opposite sides thereof and are rigidly fixed thereto. These standards are rigid from end to end or non-adjustable or bendable in any way and support the three shield sections C, D and E.

The upper shield section C is pivotally connected near its upper end with the upper ends of the standards in the manner indicated at *c* by suitable devices which serve as pivots for the shield sections and also locks by means of which the shield may be held in its adjusted position. The shield section C consists of a transparent pane or plate supported by a frame comprising an upper frame piece *c'* and side frame pieces *c''*, the lower or outer edge of the plate being frameless. The shield section C is so mounted that it may hang in a vertical plane in the direct line of vision (Fig. 4), and at this time it may be held firmly in place by the locking devices above mentioned. The upper shield section C it will be observed is mounted to swing about a fixed horizontal axis passing through the upper portions of the standards and when said upper shield section is lowered or in closed position it is disposed in substantially the same vertical plane as the main lower shield section. The main lower section D is pivotally connected to the posts B by the devices *d* which also serve to lock or hold the lower section in any adjusted position. The main lower section D is mounted to move to the desired extent about a fixed horizontal axis passing through the middle portions of the standards which is directly below the axis about which the upper shield section turns. Said lower section D is provided with a frame extending across its lower edge, as indicated at *d'* and along its opposite sides as indicated at *d''*. Its upper edge is frameless. The auxiliary section is provided with a frame extending across its lower longitudinal edge *e*, as indicated in Fig. 4, and along its sides, as indicated at *e'*. Its remaining longitudinal edge is frameless, as shown in the drawings. The auxiliary section is pivotally connected with the rigid posts B. This may be accomplished in various ways, but according to my present invention it is important that the hinge or pivot to the auxiliary section should not be movable or adjustable, certainly to no great extent relatively to the posts. The posts may be provided with brackets *b*, as indicated in Fig. 9 by which a pivotal connection between the shield section E and the posts may be made. These brackets may be rigidly formed on the posts or may be attached thereto. As indicated in Fig. 9 the axis about which the auxiliary section swings is a trifle above the axis about which the main lower section D is adjusted.

65 The auxiliary section is adapted to lie close

to the main lower section in a vertical plane, as shown in Figs. 5 and 7 to swing therewith to an inclined position, as shown in Figs. 4 and 6 or to move independently thereof to a raised position, as shown in Figs. 3 and 8. 70

The auxiliary section E is mounted to swing about a horizontal axis which is disposed in a different vertical plane from that in which the main lower shield section D is mounted. The posts or standards B are provided on each side with a plurality of bearings, one set of bearings located in one vertical plane are for the main lower shield section, while the other set of bearings, located in a different vertical plane, are for the auxiliary shield section. 75

It will be observed that the auxiliary lower section is adapted to swing inward with the main lower section and that it may be raised and held in the direct line of vision when the lower section is in either its open or closed position. It will furthermore be observed that the auxiliary section swings outward on its hinge and this it can do with perfect freedom. When the shield sections are arranged in the manner indicated in Fig. 6, a rain guard is provided by the upper section while the two lower sections are moved inward or opened for ventilating purposes. When the shield sections are arranged in the manner shown in Fig. 7 a rain guard is provided while the lower portion of the shield as a whole is closed. Fig. 8 shows an arrangement by which the upper portion of the shield is closed, a rain guard is provided and ventilation is afforded. Other adjustments of the shield section are indicated in the drawings and the purposes therefor will be well understood. 90

100 In Fig. 3 I have shown how the auxiliary section may be moved inward in order that its front face may be easily cleaned.

110 While I have shown the preferred way of constructing a wind shield embodying my improvements, it will be understood that some features of my invention may be embodied in a shield wherein the details of construction are different. While I prefer to mount the shield sections between rigid 115 posts, in the manner above specified, said sections having transparent panes or plates with frameless contiguous edges, as above explained, may be supported in other ways, and this feature of my invention will be 120 separately claimed as this feature of my invention, broadly considered, is believed to be novel.

125 I claim as my invention:

A wind shield comprising: upright standards, spaced apart, a pivotal center at the upper ends of the standards, two pivotal centers, one behind the other intermediate the upper and lower ends of the standards, three shield sections, one mounted on the 130

upper pivotal center to swing from a normal substantially vertical position into a forwardly inclined rain shed position, two lower shield sections mounted on the intermediate pivotal centers to move both of said sections from a normal substantially vertical position to an inwardly inclined ventilating position and to move one of said lower sections into an inverted upright or

into an inverted rearwardly inclined position above the other lower section when the upper section is in its rain shed position.

In testimony whereof, I have hereunto subscribed my name.

EDWARD B. HESS.
